UNITED STATES PATENT OFFICE

HANS EISNER, OF BERLIN-TEMPELHOF, AND HERMANN VOLLMER, OF BERLIN-
HALENSEE, GERMANY

PROCEDURE IN THE PRODUCTION OF A PERFUME OR COSMETIC

No Drawing. Application filed April 20, 1929, Serial No. 356,872, and in Germany June 11, 1926.

Fatty oils were employed in olden times for the care of the body, especially after bathing, in order to make the skin supple. Lately the attempt has again been made to use fatty oils for the purpose, but it has been found troublesome because the skin remains greasy for a very long time, and on this account in particular the linen is soiled. This same circumstance has so far prevented the production of a serviceable perfume with an oil base.

We have found that the above disadvantages can be obviated by mixing fatty oils with a volatile or essential oil sufficient in quantity to produce a substantial decrease in viscosity and greater than the amount necessary and usual for perfuming. Our invention is applicable to fatty oils of plant origin, i. e. vegetable oils, and to oils of mineral origin, for example paraffin oil. Essential oils are, by themselves, clear and liquid and do not grease. If these oils are mixed with fatty or mineral oils, there is the surprising result that even relatively small additions of volatile oils markedly lower the viscosity of the substances, and that they are easily and quickly absorbed by the skin.

This alteration of the viscosity does not take place in direct ratio proportionally to the parts of e. g. paraffin oil and essential oil, but follows a law, the course of which may be expressed by means of a hyperbolic curve.

When one sets out the viscosity of the mixture in relation to the proportionate ratio of the thin liquid ingredient, the resultant curve is in the shape of a hyperbola. Even with a minute admixture of the thin ingredient the viscosity is relatively near to that of the said thin component. It may even occur that the viscosity of the resultant mixture falls below that of the thin ingredient.

For instance an addition of 10% lavender oil to a paraffin oil reduces the viscosity of the mixture to half the viscosity of the paraffin oil. An addition of 20% lavender oil reduces the viscosity of the mixture to about a quarter. An addition of 30% lavender oil lowers the viscosity to about a seventh. As seen from these data the strictly hyperbolic

nature of the curve of viscosities extends only to concentrations of essential oil amounting to about 20%. The addition of essential oil beyond this point does not produce the same proportionate change in viscosity.

It has further been proved by experiment that volatile oils in union with the fatty oils not only possess the property of bringing about an overwhelming reduction in the viscosity of the mixture, but entirely new compounds are formed. It is substantiated that the component parts of the mixture mutually dissolve.

In many cases the use of essential oils is not to be recommended on account of their odor, or also on account of their high price, especially for technical uses. The property of reduction of viscosity by definite admixtures is not only essential for the employments of the afore-said substances as cosmetics or perfumes, but is also obviously important in technical connections.

Examples of substances which lend themselves readily to use in our process are such essential oils as lavender oil and benzyl-benzoate. As has been emphasized it is important that the substances in the basic oil mutually dissolve or mix thoroughly, and show curves of viscosity in the solution or mixture that are strongly convex in their ratio to the axis of the compound. As a rule a 5 to 10% admixture suffices to reduce the viscosity to a mere fraction of the original one. The addition of 20% of an essential oil is usually sufficient for all purposes.

On the oils being mixed, a cloudiness appears first of all. This is of different degrees in different oils. Under certain conditions it disappears of itself on the mixture being left standing for a longer time. However if the essential oil is irradiated, cloudiness does not appear in the compound. Rays which act chemically, e. g. ultra-violet rays, are suitable for irradiation. A mercury quartz lamp can be used as the apparatus in this process. The addition of essential oil also increases the effect of the paraffin oil. Irradiation also promotes this effect.

Any cloudiness which arises in the course of mixing can be removed by heating, as well

as by irradiation of the admixtural component before or after the mixing with the basic oil.

5 The essential oils e. g. lavender oil, are photo-active. They can furnish effective oxygen or (when water is present) hydrogen.

10 As the essential oils generally have the property described, the most varied scents can be produced which is particularly important for the production of perfumes with a viscous base. With analogous treatment a perfume with a viscous base forms simultaneously a cosmetic.

15 The following example is given of a body oil serving as a cosmetic: 10-30 parts of a volatile oil, e. g. lavender oil, are added to 70-90 parts of an inactive hydrocarbon of viscous consistency, e. g. paraffin oil. The volatile oil is energized by irradiation according to the quantity added (compare below). The volatile oil or the mixture is exposed in a thin layer for five minutes to the rays of the so called Bachschen mercury quartz-lamp at a distance of 60 cms., for the 20 purpose of clarifying and energizing it. The period of irradiation can be shortened by bringing the lamp closer. The most favourable values depend on practical experiment.

25 We claim:

30 1. As a new product suitable for use as a cosmetic or a perfume, a composition of matter comprising an oil, selected from a group consisting of fatty oils and paraffin oil, admixed with from 5 to 20 per cent by weight 35 of an essential oil; the said oils being mutually dissolved, the composition being free from cloudiness and the liquid mixtures possessing viscosities which follow a substantially hyperbolic curve.

40 2. The composition of claim 1 in which the essential oil is lavender oil.

3. The composition of claim 1 in which the essential oil is lavender oil and the oil is paraffin oil.

45 4. As a new product suitable for use as a cosmetic, a composition of matter comprising paraffin oil and approximately 5 per cent by weight of lavender oil.

50 5. In the production of cosmetics, the process which comprises adding a small proportion of an essential oil to an oil, selected from a group consisting of fatty oils and paraffin oil, and irradiating the same until cloudiness disappears and mutual solution is produced.

55 In testimony whereof we affix our signatures.

HANS EISNER.
H. VOLLMER.
